UNITED STATES PATENT OFFICE.

VICTOR E. EXTROM, OF MINNEAPOLIS, MINNESOTA.

DESIGN FOR A COMBINED CIGAR LIGHTER AND ADVERTISING-DISPLAY STAND.

Application filed August 28, 1926. Serial No. 18,890. Term of patent 3½ years.

To all whom it may concern:

Be it known that I, VICTOR E. EXTROM, a citizen of the United States, residing at Minneapolis, in the county of Hennepin, and State of Minnesota, have invented a new, original, and ornamental Design for a Combined Cigar Lighter and Advertising-Display Stand, of which the following is a specification, reference being had to the accompanying drawing, forming part thereof.

The figure is a perspective view of the article showing my new design.

I claim:

The ornamental design for a combined cigar lighter and advertising display stand, as shown.

VICTOR E. EXTROM.
